UNITED STATES PATENT OFFICE.

FELIX O'DONNELL, OF PAWTUCKET, RHODE ISLAND, ASSIGNOR OF ONE-HALF TO SUSAN A. BROWN, OF PAWTUCKET, RHODE ISLAND.

STOP-MOTION FOR CLOTH-TAKE-UP ROLLS.

SPECIFICATION forming part of Letters Patent No. 788,168, dated April 25, 1905.

Application filed April 25, 1903. Serial No. 154,257.

To all whom it may concern:

Be it known that I, FELIX O'DONNELL, a resident of the city of Providence, in the county of Providence and State of Rhode Island, have invented certain new and useful Improvements in Warp Stop-Motions; and I do hereby declare that the following is a full, clear, and exact description thereof, reference being had to the accompanying drawings, and to the letters of reference marked thereon, which form a part of this specification.

This invention relates to cloth-take-up mechanism for looms, and has for its object the production of a simple mechanism which will cause the take-up roll to stop feeding the instant the weft-thread is broken or run out of the shuttle, thus effectually preventing the weaving of thin places in the goods. It is fully explained in this specification and illustrated in the accompanying drawings.

Figure 1 is a sectional side elevation showing the cloth-take-up mechanism and my connection between the weft-feeler and the pawl on the take-up roll. Fig. 2 is a perspective view showing my mechanism to be operated in connection with the loom stop-motion to stop the take-up roll. Fig. 3 is a modification showing my device connected direct to the sliding weft-feeler plate and arranged to be operated independent of the ordinary loom stop-motion.

Referring to the drawings, A is the loom-frame, and B the breast-beam fixed thereon.

C is the cloth-take-up roll, which is driven in the manner well known to those skilled in the art through the sand-roll D, gear E, pinion F, and ratchet-wheel G, all of which are actuated by the engagement of the driving-pawl *i* with the ratchet-wheel G. This pawl is operated to move vertically by its connection with the lever V, which lever is held to be raised and lowered by the rotating cam S on the cam-shaft J. This ratchet-wheel G is held to move back and forth with the reciprocating pawl unless prevented from its backward movement by the engagement of pawl H with the teeth of the wheel to hold it still while pawl *i* goes down for another tooth,

by which the wheel is fed ahead on the next upstroke of this pawl *i*. This pawl is pivoted to the frame at I and has an upwardly-extending arm *m*, with which my new device comes in contact to raise the pawl. The guide-plate *d* is secured to the top of the breast-beam between the woven cloth and the end frame. A plate *d'* is fitted to slide in the recess in said guide-plate. A weft-fork *h* is held on a pin in the inner end of the sliding plate *d'*, so that the weft-thread *a* from the shuttle to the cloth will come in contact with the lower part *c* of the fork and tip the back end up when the lay comes forward to beat up the filling.

A lever *V* is pivoted at one end to the frame on a stud *t*, with its free end resting on the cam S. This lever *V* has an arm *U* extending up with its upper end in the recess of the sliding plate *d'* in position to strike against the projection *h'* on the end of the weft-fork lever *h* when it is not raised out of the path of this reciprocating lever by the fork catching against the weft-thread *a* as the lay comes forward. The outer end of this sliding plate *d'* is grooved transversely at *e* to receive one end of the lever *K*, which lever is pivoted at its opposite end to the outer end of the frame and is for the well-known purpose of engaging and releasing the shipper-lever *L* to stop the loom when the weft-fork fails to catch the thread *a* and also to be acted upon when the shuttle fails to enter the shuttle-box by mechanism not shown.

R is a lever or dog pivoted to the frame at *r*, the lower end of which engages the arm *m* of the pawl *H*, and its upper end is shown in Fig. 2 as being connected to the starting-lever *K*, by which it is actuated to operate on the pawl *H* and hold it out of engagement with the ratchet-wheel *G* when the lever *K* is thrown back by either of the motions described above, thereby instantly stopping the feed of the take-up roll and warp let-off.

In Fig. 3 the dog *R'* is provided with a lateral arm or projection adapted to fit in groove *e* in the end of the fork-plate. The shipper-operating lever is provided with a finger or projection *K'* extending across the top of

the plate d' , whereby the latter is held down in place, but free to slide independent of said finger or projection. This form of my invention is designed more particularly for weft-replenishing looms, so that the warp-feed may be stopped and held at rest until the shuttle has been replenished and laying the thread again correctly before the warp will start to feed ahead.

- 10 The operation of my invention is further explained as follows: In the ordinary looms when the weft-thread runs out or breaks and the fork fails to find the thread when the lay beats up the shipper or starting lever is released in the manner described above and allowed to spring forward in the well-understood way, throwing the driving-belt from the tight to the loose pulley and stopping the loom. All of these operations are performed 15 very quickly, but not quick enough to prevent the shuttle from being thrown several times back and forth across the lay, and the warp is fed ahead several picks before the loom is entirely stopped. This feeding 20 ahead of the warp and the woven part of the fabric when there is no weft-thread laid to be beat up causes a thin place to be left in the cloth, to avoid which requires careful attention from the operator. By my method of 25 connecting the weft-fork h or the lever K to the cloth-take-up-actuating mechanism as above described the weaving of these thin places in the goods is effectually prevented. My device for accomplishing this is extremely 30 simple and effective in its construction and operation, and it may be connected to and operated on any common loom. It has also proved itself very effective when used in con-

nexion with the weft-replenishing type of loom, in which case the modification shown 40 in Fig. 3 is preferred, as it allows the loom to continue to run while the shuttle is being replenished, but stops the goods from feeding ahead until the shuttle is again laying the filling into the web, when the cloth automatically starts feeding ahead again.

Having thus described my invention, what I claim as new, and desire to secure by Letters Patent, is—

1. A cloth-take-up mechanism comprising 50 a take-up roll, a ratchet-wheel and detent-pawl for operating said roll, a weft-fork, a supporting-plate therefor, a guide in which said plate reciprocates, a shipper-operating lever having a finger extending transversely 55 across the top face of said plate, whereby the latter is held in said guide, and a pivoted dog operated by said plate and normally engaging said detent-pawl.

2. A cloth-take-up mechanism comprising 60 a take-up roll, a ratchet-wheel and detent-pawl for operating said roll, a weft-fork, a supporting-plate therefor, a guide in which said plate reciprocates, a shipper-operating lever having a finger extending transversely 65 across the top face of said plate, whereby the latter is held in said guide, and a pivoted dog having a laterally - extended arm engaged with said plate, said dog normally engaging said detent-pawl.

In testimony whereof I have hereunto set my hand this 24th day of April, A. D. 1903.

FELIX O'DONNELL.

In presence of—

HOWARD E. BARLOW,
CHAS. P. DAY.
